The ornamental design for a bedstead as shown and described.

DESCRIPTION

FIG. 1 is a top front left perspective view of a bedstead showing my new design;

FIG. 2 is a front elevational view of the bedstead thereof;

FIG. 3 is a rear elevational view of the bedstead thereof;

FIG. 4 is a left side view of the bedstead thereof;

FIG. 5 is a right side view of the bedstead thereof;

FIG. 6 is a top plan view of the bedstead thereof;

FIG. 7 is a bottom plan view of the bedstead thereof; and,

FIG. 8 is a perspective view of the bedstead thereof, shown in an environment of use.

The broken lines in the drawings are for the purpose of illustrating portions of the bedstead that form no part of the claimed design. The additional broken lines shown in FIG. 8 are directed to environment in use and for illustrative purposes only and form no part thereof.
